DESIGN FOR A COMBINED SHOE INSOLE AND COVER

Martine Kane, New York, N. Y.

Application April 24, 1943, Serial No. 110,027

Term of patent 3½ years

To all whom it may concern:

Be it known that I, Martine Kane, a citizen of the United States of America, residing in New York city, county of New York, and State of New York, have invented a new, original, and ornamental Design for a Combined Shoe Insole and Cover, of which the following is a specification, reference being had to the accompanying drawing, forming part thereof.

Fig. 1 is a top plan view of a combined shoe insole and cover showing my new design.

Fig. 2 is a bottom plan view thereof.

Fig. 3 is an edge view thereof.

I claim:

The ornamental design for a combined shoe insole and cover, substantially as shown.

MARTINE KANE.
